UNITED STATES PATENT OFFICE.

CARL O. EKVALL, OF NEW YORK, N. Y.

PATCH-APPLYING MECHANISM FOR WINDOW ENVELOPES.

Application filed December 3, 1921. Serial No. 519,723.

To all whom it may concern:

Be it known that I, CARL O. EKVALL, a citizen of the United States, and a resident of the city of New York, borough of Brooklyn, county of Kings, and State of New York, have invented a certain and useful Improvement in Patch-Applying Mechanism for Window Envelopes, of which the following is a specification.

10. This invention relates to a machine for manufacturing the well known type of envelope known as the "outlook" or "window" envelope, wherein an opening is formed in the body of the envelope blank and a strip 15 of thin, transparent paper or like material is secured over the opening so that the address, which is placed on the enclosure in such a manner as to register with the opening, can readily be seen through the transparent strip placed over the opening.

This machine relates to the means for applying the thin transparent strips to the envelope blanks and over the opening therein and the object of this invention is to 25 simplify the mechanism for applying said strips and to produce a patch-applying mechanism which will work with great speed and to eliminate various objectionable features found in present machines of this character.

These and other objects are accomplished by my invention, a more particular description of which will appear below.

Reference is to be had to the accompanying drawing forming part hereof in which—

Figure 1 is a side elevation of the portion of my improved machine for gumming the envelope blanks, and also showing the plunger mechanism and patch carrier, portions of the same being shown in section.

Figure 2 is a plan view of the machine, portions of the same being shown in section.

Figure 3 is a view of the portions of the machine used for removing patches from the pile and transporting the same successively to the patch carrier which applies them to the envelope blanks.

Figure 4 is a plan view of the blank-creasing plunger and the patch carrier, parts of the same being shown in section, the section being taken on the line 6—6 of Figure 5 looking in the direction of the arrows.

Figure 5 is a sectional view on the line

5—5 of Figure 4 looking in the direction of the arrows and also showing the blank-creasing plate and the folding bed.

Figure 6 is a view of the under side of the creasing plunger and the patch carrier.

Figure 7 is a plan view of an envelope blank, and

Figures 8, 9, 10 and 11 are diagrammatic views showing the method of operation of the creasing plunger and patch-applying member.

Throughout the various views of the drawing, similar reference characters designate similar parts.

In the embodiment of my invention as I have shown it herein, I have not embodied therein many features of construction peculiar to machines for making envelopes, as they are well understood and need no specific description here for the purpose of making my invention clear.

A pile of blanks indicated at 1 in Figure 1 is placed upon a suitable support 2. Above this is a frame 3 provided with bearings 4 in which a rod 5 is vertically reciprocated. This rod 5 is vertically reciprocated by a series of levers, the inner lever 6 being fulcrumed to an upright portion 7 of the frame and the opposite end of said lever 6 is pivotally connected to a link 8 secured to the rod 5 by means of a clamp 9.

Mechanism is secured to the levers operated by a cam or other desired means (not shown) for moving the levers so as to give the rod 5 vertical reciprocation.

The rod 5 carries a head 10. To this head are pendently secured three gumming dies, 11, 12 and 13. These dies are each conformed in shape to the line of gum which is to be applied to the blank and the lower edges of each of these dies are provided with rubber strips 14 so as to give an even impression of the gum on the blank. The dies 11 and 13 are employed for the purpose of applying the gum to the upper and lower flaps of the envelope blanks and the die 12 is so shaped that it will apply the gum around the opening 15 previously formed in the blank such as shown in Figure 7.

Gumming rollers 16 which are moved back and forward below the gumming dies to apply gum thereto, are mounted on a shaft 17 located underneath the gumming dies 11, 12 and 13, the shaft 17 being supported to

rotate in bearings 18 which bearings are arranged to slide on the rods 19. The gumming rollers 16 are drawn back and forth below the dies by suitable cam mechanism, 5 connected to the shaft 17 by the arms 98 and links 99.

Located below the gumming dies 11, 12 and 13 and also below the gumming rollers 16 is a stripper plate 21 shown in plan in 10 Figure 2. This plate is provided with apertures 22 suitably formed and conforming to the shape of the gumming dies. The under surface of the stripper plate is provided, adjacent to the edges of the apertures, 15 with the stripper flanges 23 which aid in the stripping or removal of the gummed blanks from the gumming dies 11, 12 and 13. These dies 11, 12 and 13 on their downward movement pass through the apertures 20 22 in the stripper plate 21 and place gun on the edges of the flaps 24 and 25 of the envelope blank and adjacent the edges of the opening 15 in the blank as shown in Figure 7.

25 The blank adheres to these dies 11, 12 and 13 and is carried upward on the return or upward movement of said dies and on such upward movement the blank is brought into contact with the stripper plate 21 which 30 arrests its further upward movement and frees it from the gumming dies. The flanges 23 act as knife edges to more effectively produce this separation. As the blank is stripped from the gumming dies, it drops 35 down upon a carrier. This carrier consists of two arms 26 having at their ends gripping hooks 27. These arms which form the blank carrier for carrying the gummed blank, are adapted to slide or reciprocate 40 in guide ways 28 formed in arms 29 on a plate 30 which latter plate constitutes the upper horizontal portion of the frame known as the blank-creasing frame. The arms 26 are connected together by a rod 31 which 45 in turn carries a link 32 and the link 32 is connected by a lever 33 to suitable cam mechanism adapted to give the arms 26 a reciprocating movement to carry the gummed blank to a position to be creased and receive 50 the application of the patch as will be hereinafter set forth.

The horizontal plate 30 is provided with an aperture 34 through which blanks are thrust by a creasing plunger. This aperture 55 is bounded by front and rear cross plates 35 and by two sides plates 36.

The frame 3 is provided with guides 37 which guides carry a rod 38. This rod 38 is given an up and down or reciprocating 60 movement properly timed with respect to the reciprocating movements of the rod 5 (Figure 1) and the movements of the carrier frame formed of the arms 26, to the end that the movement of the envelope 65 blank from the completion of the gumming

operation to the inception of the folding operation will be continuous and the application of the patch to the blank will be had without any interruption of that movement. 79

The rod 38 carries a projection 39 to which is pivoted a link 40; said link being pivoted to a lever 41 leading to an appropriate part of the machine which, through its operation, will raise and lower the rod 38 in synchronism with the other movements heretofore described. 75

Secured to the lower end of the rod 38 is the creasing plunger 43. The plunger 43, which forms part of the blank-creasing mechanism, is shown in section in Figures 8 to 11 inclusive which figures show the various steps in the folding and patch-applying operation. 80

A plan view of the plunger is shown in Figure 4. The plunger consists of a flat rectangular plate secured to the lower end of the rod 38 in a boss 44 which is secured to the plunger by screws 45. The plunger is provided on its under face with a shallow elongated recess 46 which extends longitudinally of the plunger. The plunger is also provided with an opening 47 extending through it, and through this opening the patch-applying member 48 is adapted to be moved after it has applied a patch as will be hereinafter set forth. 90

The patch-applying member 48 acts as a patch carrier for single successive patches and transports the same to the point where they are applied, as will be set forth herein-after. The patch-applying member consists of a hollow plate having an interior chamber 50 and a plurality of ports 51 leading from said chamber to the under face of 100 the patch-applying member. The patch-applying member 48 corresponds in outline to the opening 47 in the creasing plunger so that the patch-applying member can lie in said opening during the application of the patch to the blank, and is movable therethrough after the application of the patch. At 52 is shown an integral lateral extension 105 on the patch-applying member and on said extension is a boss 53 in which is secured a tubular rod 54 which extends upwardly and is movable through the guides 37 in the frame 3. In order to reciprocate the patch-applying member, the tubular rod 54 is connected to a link 55 which is pivotally connected to an arm 56 on a bell crank lever pivoted on a shaft 57 secured on the machine. The other arm 58 of the bell-crank lever is connected at its end to a rod 59 which extends to suitable cam mechanism 115 which acts, through the medium of the mechanism just described, to vertically reciprocate the patch-applying member. 110

The rod 54 being tubular provides a continuous air-passage 60 through which suc- 115

tion is exerted, said suction being caused by a pump or the like (not shown) which is connected to the rod 54 by a flexible tube, a portion of which is disclosed at 61 in Figure 1, such connection in no way interfering with the reciprocating movement of the patch-applying member.

The initial or raised position of the patch-applying member 48 and the creasing plunger 43 is disclosed in Figure 1 which indicates the relation of the parts at their highest point of ascent with the patch-applying member extending below the creasing plunger and in position to receive and retain a patch on its under face by suction exerted through it.

The means for supplying successive single patches to the patch-applying member will now be described.

At 62 is the patch table or support which receives and holds a pile 63 of the thin, transparent patches within a cage 64 secured on the table. The cage 64 is provided with an upright 65 in which is pivoted a tubular picker rod 66 having a laterally bent end 67 provided with a pair of downwardly extending nipples 68 through which suction is exerted to lift successive patches from the pile 63. As shown in Figure 2 the laterally bent end of the picker 66 extends crosswise of the patches and is located adjacent one end of the same and near a patch gripper composed of parts 73 and 74 which supply the successive patches to the patch-applying member 48.

The rear end of the picker 66 is supported on a grooved pulley 69 which is slidably mounted on a shaft 70. This shaft is secured to and extends from one end of a rocker arm 71, which rocker arm is pivoted in a bracket 72 secured to a part of the machine.

The outer end of the rocker arm is connected to suitable operating mechanism to the end that when said outer end of the rocker arm is moved, the lateral end 67 of the picker 66 will be tilted downward to rest on the uppermost patch in the pile. Through suitable mechanism not shown suction is exerted through the tubular picker 66 to cause the uppermost patch to adhere to the nipples 68 on its lateral end 67. The lateral end of the tubular picker 66 is then lifted and it raises one end of the uppermost patch 86 as disclosed in Figure 3, when said patch is grasped by a pair of gripping fingers 73 and 74 and brought to the patch-applying member 48 for application to a blank.

On its way to the patch-applying member 48 the patch is aligned by movement through pairs of aligning guides 75. The grippers are mounted on an arm 76 which is secured on a sleeve 77 slidable on a rod 78 extending across the machine. The means for sliding said sleeve backward and

forward on the rod 78 comprises a link 79 connected at its end to a lever actuated by suitable cam mechanism not shown.

The opening and closing of the grippers 73 and 74 is effected by means of a tripper member 81 having a roller 82 mounted on its free end, and a dog 83. At 84 is a stop secured on a bracket 85, and said stop is adapted to contact with the dog 83 to permit the grippers to close on a lifted patch 86, such closing of the grippers being effected by a spring 87 which brings the movable gripper 73 down on the stationary gripper 74 so that they grip the patch 86 between them. The grippers which are then holding the patch move across the machine until they reach a point with the patch held below the patch-applying member 48. Suction being exerted through the patch-applying member causes the patch to adhere to the under surface of said member and the grippers open leaving the patch on the under surface of said patch applying member and ready for application to the blank. The opening of the grippers to release the patch at this point is effected by means of a projection 88 which strikes against the roller 82 and separates the grippers. The open grippers are then carried back to receive a new patch and the creasing plunger 43 and patch-applying member with its attached patch descend to apply the patch to the blank as will now be described.

In the drawings Figures 8 to 11 indicate the various steps in the operation of applying the patch to the blank and the positions of the creasing plunger and patch-applying member. In Figure 8 a patch 86 is shown attached to the patch-applying member 48 by suction exerted through said patch-applying member. A gummed blank 89 is shown resting upon the creasing plate and the creasing plunger is descending.

In Figure 9 the creasing plunger 43 is shown contacting with the blank 89 and beginning to force the same through the opening 34 in the creasing plate to crease the blank. At this point it will be seen that the patch-applying member is located within the opening 47 in the creasing plunger and said patch-applying member and creasing plunger are moving downward at the same speed. The patch-applying member holds its attached patch 86 within the recess 46 in said plunger and away from the surface of the blank. The creasing plunger 43 and the patch-applying member 48 continue to move downward together at a uniform rate of speed, the creasing plunger forcing the blank 89 down towards the folding bed 90 with the patch-applying member at no time coming into contact with the blank and holding its attached patch 86 away from the same. As the blank nears

the folding bed 90 and reaches the disclosed position in Figure 10, the current of air in the patch-applying member 48 is reversed and forms a blast of air which 5 blows the patch 86 off from the under face of the patch-applying member and onto the blank. This constitutes the lowest point of descent of the patch-applying member 48 and it then begins its upward movement 10 while the creasing plunger 43 continues downward forcing the blank with its attached patch down on the folding bed 90. Thereafter the creasing plunger moves upward causing the patch-applying member 15 to pass through its opening 47 so that the creasing plunger 43 removes to the initial position of the device disclosed in Figures 1 and 8 with the patch-applying member 48 in position to receive a new patch. The 20 patched blank remains on the folding bed where it is acted upon by a mechanism which folds down its flaps and produces the completed envelope. This cycle of operation is repeated as long as the machine is 25 in operation.

It will be noted that the patch applying member at no time contacts with the blank and consequently does not press the patch 86 upon the blank as is done in many of the 30 present forms of machine but rather blows the same thereon by an air blast. This form of machine is speedy in operation, prevents the patches from sticking to the patch-applying member and as the patch- 35 applying member is at no time brought into contact with the blank, the possibility of gum reaching the under face of the patch-applying member is avoided.

From the foregoing it is obvious that my 40 invention is not to be restricted to the exact embodiment shown but is broad enough to cover all structures coming within the scope of the annexed claims.

What I claim is:

45 1. In a machine of the class described, a blank creasing plate, a folding bed, an apertured creasing plunger adapted to move a blank through said creasing plate down to the folding bed, a patch-applying member 50 adapted to receive a patch below the creasing plunger when said plunger is in its raised position, means for moving said patch-applying member downward while the same is located in the aperture in the 55 creasing plunger, means for causing a patch to be applied to a blank while the same is being moved by the creasing plunger and means for terminating the movement of the patch applying member at a distance from 60 the folding bed, while said creasing plunger thereafter continues its movement of the patch blank to the folding bed.

65 2. In a machine of the class described, a blank creasing plate, a folding bed, an apertured creasing plunger, an independently

movable patch-applying member adapted to receive a patch at a point below the creasing plunger when said plunger is in its raised position, means for moving said plunger and patch applying member towards the 70 folding bed with the patch-applying member lying within the aperture in the creasing plunger, means for terminating the movement of the patch-applying member at a distance from the folding bed after the 75 patch has been applied and means for causing the creasing plunger to thereafter move the patched blank down to the folding bed.

3. In a machine of the class described, a reciprocating plunger having an opening, a creasing plate through which a blank is forced by said plunger, a bed plate below said creasing plunger, means for reciprocating said plunger to cause the same to force a blank through the creasing plate and down 80 to the bed plate and a patch-applying member adapted to receive a patch at a point below the creasing plunger and adapted to lie within the opening in the creasing 85 plunger and apply a patch to the blank at 90 a point intermediate of the creasing plate and the bed plate.

4. In a machine of the class described, a reciprocating blank-creasing plunger, a base to which a blank is forced by the plunger 95 said plunger having an opening extending through it, a reciprocating patch-applying member adapted to receive a patch below the plunger and lie within said opening during downward movement of said plunger and the patch-applying member and adapted to apply a patch to a blank during such downward movement and before the blank reaches the base.

5. In a machine of the class described, a creasing plate, a movable plunger having a recess, an opening passing through that portion of the plunger in which the recess is located and a patch applying member adapted to receive successive patches at a point below the plunger and fit within said opening and hold a patch within said recess.

6. In a machine of the class described, a reciprocating creasing plunger having an opening and having a recess on its under face, a reciprocating patch-applying member, pneumatic means for retaining a patch on the under face of said patch-applying member, means for vertically reciprocating said plunger and patch-applying member independently of one another, a creasing plate and a bed plate and means for causing the patch-applying member to apply a patch to a blank at a point of termination of downward movement of the patch-applying member while said blank is being moved downwardly towards the bed-plate.

7. In a machine of the class described a creasing plate and a bed plate, a creasing plunger for forcing a blank through the 130

creasing plate and towards the bed-plate, said creasing plunger having an opening, and a patch-applying member movable through said opening and adapted to lie 5 with the opening during movement of the blank towards the bed-plate and adapted to apply a patch during such movement, said patch-applying member terminating its movement toward the bed plate at a distance from said bed plate.

8. In a machine of the class described an apertured plunger adapted to force an en-

velope blank down to folding means and an independently movable patch-applying member having its limit of downward movement terminating at a point above and away from said folding means and adapted to lie within said plunger and apply a patch to the blank during its movement towards the folding means.

Signed at the city, county and State of New York this 1st day of December, 1921.

CARL O. EKVALL.
